Lucy Tracey, Attorney

UNITED STATES PATENT OFFICE.

OSCAR KUHNER, OF COLUMBUS, OHIO.

TEMPORARY END CLOSURE FOR LOCOMOTIVE VALVE CHAMBERS.

Application filed October 14, 1920. Serial No. 416,793.

To all whom it may concern:

Be it known that I, OSCAR KUHNER, citizen of the United States, residing at Columbus, in the county of Franklin and State of Ohio, have invented certain new and useful Improvements in Temporary End Closures for Locomotive Valve Chambers, of which the following is a specification.

This invention relates to an improved end closing device for locomotive valve chambers and has as one of its principal objects to provide a device of this character whereby the steam ports of the valve chambers of a locomotive may be blocked off so that water under pressure may be introduced into the locomotive boiler for hydraulically testing the superheater, header and steam pipes.

The invention has as a further object to provide a device of this character which will eliminate the necessity for removing the locomotive smoke box front, steam pipes and other parts necessary to permit removal of said pipes, as is now commonly practiced, in order to make sure that the superheater, superheater header and steam pipes are in proper condition.

And the invention has as a still further object to provide a device which may be readily applied and removed and which will be constructed to meet the conditions of valve chambers before as well as after being rebored.

Other and incidental objects will appear hereinafter.

35 In the drawings:

Figure 1 is a longitudinal sectional view showing my improved device in position within a locomotive valve chamber of conventional design.

40 Figure 2 is an end elevation of the device.

Figure 3 is a sectional view on the line 3—3 of Figure 1, looking in the direction of the arrows, and

45 Figure 4 is an edge elevation of one of the expansible closure rings employed.

In carrying the invention into effect, I employ a body bar or rod 10 provided at its ends with reduced squared extensions forming handles 11. Threaded upon the end portions of the bar are stop nuts 12 and threaded upon the bar to abut said nuts are frustoconical expanders 13 having the smaller ends thereof presented outwardly. Freely fitting

upon the bar and slidable thereon are annular heads 14 having flat inner faces and counterbored centrally at their outer sides to provide ground seats 15. Threaded upon the outer end portions of the bar to coact with said heads are adjusting nuts 16 provided at their inner ends with annular bosses 17 ground to fit said seats providing water-tight joints between the nuts and the heads. The heads are each equipped with a pair of handles 18 so that said heads may be readily manipulated. Seating against the flat inner face of each of the heads is a set of segmental clamps 19. As particularly shown in Figure 3 of the drawings, four clamps are comprised in each set and engaging through suitable radial slots in the clamps are cap screws 20 slidably connecting the clamps with the heads. At their inner ends the clamps are formed with beveled end walls mating to define tapered openings adapted to receive the expanders 13 while at their outer end portions, the clamps are stepped at the inner sides thereof to provide concentric annular seats 21 and 22. Fitting in the seats 21 to normally lie flush with the outer end edges of the clamps as well as flush with the seats 22 thereof are split expansible rings 23. One of said rings is shown in detail in Figure 4. The rings are, of course, resilient and, as will be observed, said rings are provided with rounded outer corners. Fitting the rounded outer corners of the rings to overlie said rings are expansible annular gaskets 24. These gaskets may be formed of any approved material and the outer margins thereof are arranged to surround the outer edges of the clamps while the inner margins thereof, which lie at substantially right angles to the outer margins, are formed to fit the seats 22 of the clamps lying against the flat inner faces of the heads 14. Threaded through the head shown at the right of Figure 1, is a drain pipe 25 arranged near the periphery of said head and formed through the adjacent clamp of the head opposite the inner end of the pipe is a drain opening 26 elongated to accommodate radial movement of the clamp so that said opening will always be in communication with said pipe. Interposed in the pipe is a shut-off valve 27 and 100 preferably arranged beyond said valve is a 105

coupling 28 so that the outer end portion of the pipe may, when desired, be readily detached.

In Figure 1 of the drawings, I have shown my improved device in conjunction with a locomotive valve chamber 29 of conventional design. As is usual, this valve chamber is integrally formed upon a cylinder 30 and leading from the end portions of the chamber into the cylinder are steam ports 31. In so far as is known, it has heretofore been necessary, in order to test and examine the superheater and superheater header, to remove the locomotive smoke box front, steam pipes and other parts necessary to permit removal of said pipes. As is well known, this is a tedious and accordingly, an expensive operation. Further, under this procedure, the steam pipes could not be tested owing to the necessity for removing said pipes. The present invention, therefore, seeks to provide a device whereby not only the superheater and superheater header may be tested, but also the steam pipes, and in such manner that the removal of the locomotive smoke box front, as well as the steam pipes and other obstructing parts, will be rendered unnecessary. To accomplish the test, the heads of the chamber are removed and the valve displaced when, as shown, the device is positioned within the chamber so that the heads 14 thereof lie at the inner sides of the steam ports 31, one of the devices being, of course, employed in connection with each valve chamber of the locomotive. By rotating the nuts 12, the heads may, of course, be adjustably positioned along the body bar 10 as desired so that the heads will be properly disposed with respect to the ports. The nuts 16 are then adjusted for shifting the heads inwardly upon the rod and advancing the clamps 19 over the expanders 13. This will, of course, result in moving the clamps radially outward and binding the gaskets 24 against the wall of the chamber. As the clamps are thus shifted outwardly the clamps of each set will, as will be readily understood, separate and the rings 23 are accordingly provided to extend across the spaces between the outer ends of the clamps for bridging said spaces and holding the gaskets throughout the entire circumference of each thereof flat against the chamber wall. Water-tight joints will thus be formed between the heads 14 and the wall of the chamber so that communication between the steam inlet and the passages 31 will be cut off. Accordingly, water may then be introduced into the locomotive boiler to stand within the superheater, superheater header and steam pipes so that by raising the water to the desired pressure, the superheater, superheater header and steam pipes may be tested. Any leakage in these parts may thus

be quickly determined. After the test, the valve 27 is opened and the water drained off through the drain pipe 25, compressed air being introduced into the boiler for expelling the water therefrom. I accordingly provide a particularly effective device for the purpose set forth and, as will now be readily understood, a device capable of adjustment to accommodate the requirements of different valve chambers both as regards length and internal diameter.

Having thus described the invention, what is claimed as new is:

1. A device of the character described including a body bar, a head upon the bar, radially movable segmental clamps carried by said head, a ring surrounding the clamps of each head, a gasket surrounding said clamps and overlying the ring, and means for shifting the clamps radially.

2. A device of the character described including a body bar, a head thereon, radially shiftable clamping means associated with the head, a ring surrounding said clamping means, sealing means overlying said ring, and means for shifting the clamping means radially.

3. A device of the character described including a body bar, a head thereon, radially shiftable clamping means slidably connected to the head, sealing means associated with said clamping means, and means for shifting the clamping means radially.

4. A device of the character described including a body bar, a head thereon, radially shiftable clamping means lying against one side face of the head, sealing means associated with said clamping means, and means for shifting the clamping means radially.

5. A device of the character described including a body bar, a head thereon, radially shiftable clamping means associated with the head, sealing means coacting with the clamping means and secured between the clamping means and the head, and means for shifting the clamping means radially.

6. A device of the character described including a body bar, a head thereon, clamping means shiftable radially upon the head and formed to provide an annular seat, a ring lying in said seat, a gasket overlying the ring coacting with the clamping means, and means for shifting the clamping means radially.

7. A device of the character described including a body bar, a head thereon, clamps carried by the head and provided with slots, pins extending through said slots engaged with the head slidably connecting the clamps with the head for radial movement, sealing means associated with said clamps, and means for shifting the clamps radially.

8. The combination with a locomotive valve chamber, of means for temporarily

closing the chamber at its ends, and means associated with the first means for draining the chamber.

9. A device of the character described including a body bar, a head thereon, radially movable clamping means carried by the head, sealing means associated with said

clamping means, means for shifting the clamping means radially, and a drain pipe connected with the head.

In testimony whereof I affix my signature.

OSCAR KUHNER. [L. S.]
